BOILER

Clarence D. Gibbs, Jenkintown, and Robert K. Miller, Allentown, Pa.

Application February 10, 1944, Serial No. 521,776

7 Claims. (Cl. 122—267)

Objects of the present invention are, first, to provide compact, reliable and efficient boiler equipment which may be arranged as a unitary structure and transportable as such; second, to effect an economy in the generation of steam; and, third, to provide an improved boiler both in respect to construction and operation.

Other objects of the invention will appear from the following description at the end of which the invention will be claimed.

Generally stated the invention comprises the improvements hereinafter described and finally claimed.

In the following description reference will be made to the accompanying drawings forming part hereof and in which,

Figure 1 is an elevational view principally in section of a boiler or steam generator embodying features of the invention.

Figure 2 is a transverse section taken on the line 2—2 of Figure 1 and drawn to an enlarged scale.

Figure 3 is a view principally in transverse section on the line 3—3 of Fig. 1 drawn to an enlarged scale and illustrating details of construction.

Figure 4 is a transverse sectional view drawn to an enlarged scale of the construction shown at the left hand in Figure 3.

Figure 5 is a sectional view drawn to an enlarged scale and illustrating the superheater tube; and

Figure 6 is a view illustrating one means by which the burners can be operated individually or in groups.

Referring to the drawings, the boiler proper may be described as follows: Two spaced parallel vertical plates 3 and 7 form one water leg of the boiler and two other plates 4 and 8 parallel to and spaced from the said plates 3 and 7 form a second water leg. The space between the two water legs constitutes a passage 6' for products of combustion. There are a series of pairs of tubes 1 and 2 each arranged one within the other with an annular space between them. The inner tubes provide combustion chambers and the space between the tubes of each pair provides water space which communicates with water in the said water legs at each end of the construction. The respective pairs of tubes are spaced from each other and heat is imparted to the outer tubes from products of combustion in tubes 1 and in passage 6'. The inner or fire tubes 1 extend at their opposite ends through tube sheets 3 and 4 and communicate at their left hand ends with air inlet duct 5 and at their right hand ends with an offtake passage 6 for products of combustion. The outer tubes 2 are mounted at their ends in tube sheets 7 and 8 and communicate with the water legs of the

boiler. There are a series of oil burners 9, one for each fire tube. These oil burners are lighted and extinguished individually or in groups according to the boiler demand. Referring to Figure 3 the oil burners are arranged to be projected into the open ends of the fire tubes and to be withdrawn therefrom. When withdrawn from the fire tubes, as shown in Figure 3, they are ignited automatically by reason of the high temperature of the air in the air inlet duct 5 and when projected into the tubes 1 they are extinguished because the supply of oil and air to them is automatically cut-off. The burners are projected by springs 11 acting upon piston heads 12 slidable in cylinders 13 and they are retracted by compressed air applied through the pipes 16 to the right hand face of the piston. When the air pressure in the pipes 16 is cut off the springs are free to operate in the manner described and the tips of the burners are projected into the tubes 1. Oil for combustion is supplied through the oil inlet 14 to the inner tips of the burners and the air is supplied around the outside of the inner tips of the burners. In this way the burner tips are kept free from deposits. 15 is an exhaust connection for the air applied to the piston. It may be noted that the movement of the burners serves to open and close the oil and air supplies.

Air for supporting combustion enters at 20, is screened at 21, and under the influence of the fan 22 driven by the motor 23, is passed downward through the duct 24 through the preheater 25 and ascends through the air inlet duct 5. The hot products of combustion pass around the coils of the steam superheater 26, descend through passage 6' around the outside of the respective pairs of tubes, and pass horizontally through the air preheater 25, and ascend through the feed water heater 27 and are by the exhaust fan 28 expelled to the atmosphere.

Referring to Figure 2, the air preheater is of the plate type consisting of long flat tubes 100 of metal separated to form alternate air and gas or hot products of combustion passages between the tubes, with the whole welded into a homogeneous unit. Ribs or vanes 101 on the tubes 100 divide the space between the tubes into numerous gas passages of square cross section. The air flows through its passages in a straight line but the gas enters across the sheets and is then redirected longitudinally along the sheets to the other end where it leaves the passages by again flowing across the sheets. The features of the gas passages are the combination of longitudinal and transverse flow, and the use of vanes 101 welded to the tubes 100 to obtain this flow.

The steam after leaving the boiler and before entering the superheater is passed through the

drums 29 and 30 which serve to remove entrained water which is returned to the boiler by way of the passages 30', 31 and 32 along with the feed water which is introduced into drum 29 by way of the connections 33 and equipment 34 after passing through preheater 27. The motor driven pump 35 serves to cause circulation of water in the boiler.

It may be remarked that the temperature of the air is sufficiently high to cause ignition of the burners when the oil supply is turned on. Initially one or more of the burners is ignited by means of a blow torch or of any other convenient means.

It may be further remarked that air for cooling the inner tips of the burners is supplied from the compressed air connection 16. From this same source air under pressure through manual control is available for operating the burners. Referring to Figure 6 the pipe a is shown as provided with a valve b and with a header c with which the pipes 16 communicate and the pipes 16 are shown as each provided with a valve d. The pipe a communicates with a source of air under pressure not shown.

When the burner is moved back and forth the piston covers and uncovers the oil supply connection 14 and, as has been said, the compressed air supply 16 is controlled manually.

The described elements are all contained in a housing 36 so that the complete unit, if desired, may be assembled and transported ready for installation. It may be remarked that the embodiment of the invention herein described may be assembled and mounted on the chassis for a wheeled frame of a locomotive.

It will be obvious to those skilled in the art that modifications may be made in details of construction and arrangement without departing from the spirit of the invention which is not limited as to such matters or otherwise than as the prior art and the appended claims may require.

We claim:

1. In a boiler or steam generator the combination of a plurality of assemblies consisting of an inner tube and an outer tube, a chamber in which the tubes are assembled, an oil burner arranged at the entrance of each inner tube, means for returning the hot products of combustion outside of the outer tube and through the chamber, means for supplying water outside of the inner tube, and an air heater supplying air to the burner and heated by the hot products of combustion.

2. In a boiler or steam generator the combination of a plurality of assemblies each consisting of an inner tube and an outer tube, a chamber in which the tubes are assembled, an air heater and means for supplying hot air to the inner tubes at a temperature sufficiently high for igniting the fuel, a series of oil burners and means to project and to retract the said burners with respect to the open ends of the inner tubes and thereby to extinguish and to ignite the said burners individually or in groups.

3. The combination substantially as described in claim 2 and in which the individual burners are connected with a compressed air supply which actuates the said projecting and retracting means to cut off and to admit oil and compressed air.

4. A steam generator or boiler comprising the combination substantially as described in claim 2 and in which the parts recited therein together

with their accessories including water legs, a steam drum, an air preheater and a steam superheater constitute a unitary structure and a housing or casing enclosing the said structure and causing it to be portable as a unit.

5. A boiler or steam generator comprising in combination spaced tube sheets arranged in pairs spaced apart and forming water legs, the space between the said legs constituting a passage for combustion gases, a series of burners outside one of said water legs, a multiplicity of inner and outer tubes arranged in pairs and spanning the said passage and of which the outer tubes communicate with the interior of the water legs and of which the inner tubes span the water legs and open through the outer tube sheets for cooperation with the said burners at one end and for the discharge of hot products of combustion at the other end, means for introducing feed water into the water legs and for withdrawing steam therefrom, means for passing hot products of combustion through the said passage between the water legs and around the outer tubes, a flue into which the inner tubes open and which is supplied with air heated to a high temperature by the products of combustion, there being provided an air heater for this purpose, means for projecting and retracting the said burners across the hot air flue and into and from the open ends of the inner tube the said burners being automatically ignited by the hot air in said flue when retracted, and means for individually extinguishing said burners.

6. A boiler or steam generator comprising in combination spaced tube sheets arranged in pairs spaced apart and forming water legs, the space between the said legs constituting a passage for combustion gases, a series of burners outside one of said water legs, a multiplicity of inner and outer tubes arranged in pairs and spanning the said passage and of which the outer tubes communicate with the interior of the water legs and of which the inner tubes span the water legs and open through the outer tube sheets for cooperation with the said burners at one end and for the discharge of hot products of combustion at the other end, means for introducing feed water into the water legs and for withdrawing steam therefrom, means for passing hot products of combustion through the said passage between the water legs and around the outer tubes, a flue into which the inner tubes open and which is supplied with air heated to a high temperature by the products of combustion, there being provided an air heater for this purpose, and means for individually lighting and extinguishing said burners.

7. A boiler or steam generator comprising in combination spaced tube sheets arranged in pairs spaced apart and forming water legs, the space between the said legs constituting a passage for combustion gases, a series of burners outside one of said water legs, a multiplicity of inner and outer tubes arranged in pairs and spanning the said passage and of which the outer tubes communicate with the interior of the water legs and of which the inner tubes span the water legs and open through the outer tube sheets for cooperation with the said burners at one end and for the discharge of hot products of combustion at the other end, and means for individually lighting and extinguishing the oil burners.
